UNITED STATES PATENT OFFICE.

JOSEPH G. KASTLER, OF DETROIT, MICHIGAN.

SASH-LOCK.

1,321,053.

Specification of Letters Patent.

Patented Nov. 4, 1919.

Application filed June 17, 1918. Serial No. 240,295.

To all whom it may concern:

Be it known that I, JOSEPH G. KASTLER, a citizen of the United States, residing at Detroit, county of Wayne, State of Michigan, have invented a certain new and useful Improvement in Sash-Locks, and declare the following to be a full, clear, and exact description of the same, such as will enable others skilled in the art to which it pertains to make and use the same, reference being had to the accompanying drawings, which form a part of this specification.

This invention relates to sash locks, and its object is a safety lock for windows that is simple and inexpensive in character having the adaptation to securely lock the upper and lower sash of a window in any predetermined relationship either open or closed to prevent movement of the sash from the outside and thus enabling the sash to be locked in open relationship without possibility of the window being opened to further extent. The novel feature of the invention is involved in the means employed to securely fasten the window that on an attempted movement of the windows when the device is in locked position tends to bind the sash to an increasing extent and thus prevent movement thereof in the frame when locked. These objects and the several novel features of the invention in its preferred form are hereinafter more fully described and claimed and shown in the accompanying drawings in which—

Figure 1 is an elevation partly in section taken on line $x-x$ of Fig. 2, showing my improved sash lock in position.

Fig. 2 is a longitudinal section of the device on line $y-y$ of Fig. 1, showing the locking lever.

Fig. 3 is a side elevation thereof.

Fig. 4 is a plan view.

The device is adapted for use on the meeting rail of the sash, it being attached as shown in Fig. 1 on the top of the meeting rail 1. The device consists of a base member 2 and a case or cap member 3 secured thereto preferably by means of lugs 4 on the cap member extending through apertures provided therefor in the base member, the ends of the lugs being peened or headed to retain the parts together. The cap member 3, as shown particularly in Fig. 3, is provided with an aperture 5 through which extends an end of the operating lever 6. This lever is pivoted as shown in Fig. 2 on

a pin 7 extending through the cap and into the base member as shown. The inner end of the lever terminates in an upwardly extending rounded portion 8 shown particularly in Figs. 1 and 2. Pivotedly mounted in the casing, by means of a pin 9 extending through opposite walls of the case, is the binding or wedging lever 9^a. This binding lever terminates within the casing in an arcuate end 10 engaging the rounded end 8 of the lever 6. The lever extends outwardly through openings 11 in the case and has a terminal portion 12 extending toward and nearly in contact with the vertical side bar 13 of the upper sash. This terminal portion 12 is recessed to receive a rubber insert 14 that is compressible in character and the said end of the lever is also provided with a pointed sash engaging portion 15.

In the position of parts shown in full lines in Fig. 1 the lever is in what I have termed normal position with the rubber insert just engaging the face of the sash bar 13. In this position of parts the sash may be raised or lowered without inconvenience but preferably, when it is desired to unlock the sash, the end of the lever 8 is turned to the right of the Fig. 1 and, by reason of the engagement of the said end 8 with the arcuate portion 10 of the lever 9, the end 12 is raised to position shown by dotted lines a out of contact with the face of the sash bar. To lock the sash the lever 8 is turned to the left of Fig. 1 which forces the lever 9 to position shown by dotted lines b in the figure, forcibly compressing the rubber insert and bringing the point 15 practically to contact with the face of the sash although preferably not quite in contact, the projecting of the rubber insert under the condition stated holding the point out of contact with the sash. With the lever in the position shown by dotted lines b if it is attempted to raise the sash bar 1 such movement tends to relatively move the lever 9 downward which tends to force the sash apart and force the point into the sash bar, as will be understood.

It is to be noted that the entire lock is carried on the sash bar 1 and that the lever 9 and rubber insert carried thereby may engage the face of the upper sash 13 at any point of its length. It is therefore evident that the sash may be locked in an open position and when so locked in such position it is impossible to draw the upper sash 13

downward to increase the opening at the upper end of the window or to force the lower sash open to increase the opening at the lower part of the window without first 5 unlocking the device.

The parts preferably are made of metal sufficient in strength to withstand any ordinary pressure that may be brought to bear thereagainst in an attempt to open a window 10 locked thereby, and it is further evident from the foregoing description that the device is simple and inexpensive in construction, and that it is adapted for use with sliding windows, and that, by arranging the 15 device with a lever of the character shown, the pressure exerted on the lever has no tendency to pull the fastening screws longitudinally out of the sash bars as with the other types of fastening devices but that 20 pressure is exerted at right angles to the screws and therefore a substantial fastening is provided very readily operated by means of a push lever and easily and readily mounted.

25 Having thus briefly described my invention, what I claim is—

1. A sash lock comprising the combination with a pair of sash members vertically 30 slideable in parallel relation, of a base member adapted to be secured to the upper cross bar of the lower sash member, a wedge member pivoted to the base to swing in a vertical plane having an end adapted to wedgingly engage a side bar of the upper sash member, 35 said member terminating within the case in an arcuate end, occupying the plane in which the lever swings and the center of which is below the pivot point thereof, an operating lever pivoted between its ends on a vertical 40 axis, the inner end of which rides in the said arcuate end of the wedge member, movement of the operating lever in one direction and engagement thereby with one

end of the arcuate part of the wedge member forcing the same into wedging relation 45 with the said upper sash and movement of the operating lever in the opposite direction correspondingly disengaging the wedge member.

2. A lock for a pair of sash members relatively movable in vertical relation consisting of a hollow case adapted to be attached to the lower sash member and having an opening through the upper surface, a wedging lever adapted for engagement with the upper sash member pivotally mounted in the 50 case and extending through the said opening, said wedging lever terminating within the case in an arcuate end, positioned in the plane in which the lever swings, an operating lever pivotally mounted in the case having one end extending outwardly 55 through the case and the other end engaging the said arcuate end of the wedging lever.

3. A lock for a pair of sash members relatively movable in parallel relation comprising a base member adapted to be secured to the meeting rail of one of the sash members, a wedging member pivoted in the base to swing in a plane at a right angle to the 60 plane of the sash toward or from wedging relation with the other sash member, the said wedging member terminating within the case below the pivot point in two ends or arms, an operating lever pivoted to swing 65 in a plane at a right angle to the plane of movement of the wedging lever and having an end extending between the said arms or ends of the wedging lever whereby movement in one direction disengages the wedging member and movement in the other causes wedging engagement thereof with the sash.

In testimony whereof I sign this specification.

JOSEPH G. KASTLER.
